UNITED STATES PATENT OFFICE.

CLARENCE SHEPHERD, OF BRIDGETOWN, WESTERN AUSTRALIA, AUSTRALIA.

WEIGHT-INDICATOR FOR LOADED VEHICLES.

1,088,463.

Specification of Letters Patent.

Patented Feb. 24, 1914.

Application filed January 25, 1913. Serial No. 744,229.

To all whom it may concern:

Be it known that I, CLARENCE SHEPHERD, a subject of the King of Great Britain, residing at Bridgetown, Western Australia, 5 Commonwealth of Australia, have invented certain new and useful Improvements in Weight-Indicators for Loaded Vehicles, of which the following is a specification.

The object of this invention is to provide 10 an appliance whereby loaded vehicles may be weighed "in situ" and the weight of the load ascertained.

The appliance is usable beneath the vehicle and mainly comprises three vertically 15 movable rods which are operatively held and mounted in their standard frame.

An embodiment of the invention is illustrated in the accompanying drawings, wherein—

20 Figure 1 is a front elevation, showing the hot water tank in section; Fig. 2 is an end elevation, showing the tank in dotted lines; and Fig. 3 is a plan view, with the tank omitted, and the head plate partly broken 25 away to disclose the dial brackets. The dials are shown in dotted lines.

In said drawings, *a* indicates the base or standard frame, made in the form shown and having the fixed flange *a*¹. The appliance 30 comprises three vertically movable rods, the central rod *b* carrying a pawl-and-ratchet device *b*¹—*b*², by means of which it may be rotated, as will be understood, the threaded lower end *b*³ of said rod working 35 in a base *b*⁴ on frame *a*, so that when such rotation takes place, the rod will be either raised or lowered, according to the direction of rotation. The ratchet *b*¹ is splined on rod *b*, so as to permit the latter to move 40 relatively thereto.

The rod *b* has a rounded upper end *c*, which fits loosely in a correspondingly-shaped socket in the head-plate *c*¹, whereon the vehicle *x*—*x* is adapted to rest, the aforementioned 45 socket having an opening *c*² communicating therewith for lubricating purposes. From said plate depend two vertically movable rods *d* and *d*¹ which are rigidly fastened thereto and extend through guide 50 openings in the cap-plate *e* and flange *a*¹. These rods are threaded, where shown, and are fitted with locking nuts *d*² and *d*³ which are designed to engage against the movable cap-plate *e*, and, also, to serve as collars for 55 adjusting the tension of the strong spiral

springs *e*¹ that are interposed between said cap-plate and flange and coiled around the rods. The afore-mentioned springs *e*¹ receive the load during the weighing action, and are standardized in order to correctly 60 ascertain the weight thereof.

To the ends of the plate *e* are connected the rods *f* and *f*¹, and these rods move up and down in unison with said plate through 65 openings in flange *a*¹ and are provided with guides *g*²; they are toothed in order to engage with the pinions *f*² which rotate the hands of the dials *f*³, whereby the weight is indicated. The dial spindles *g* and pinions *f*² are held in the brackets *g*¹ secured on the 70 standard, as clearly shown in Fig. 3.

In order to overcome any cold temperature troubles in relation to the springs, *e*¹ a double-walled chamber or tank *j* is provided, which surrounds the springs and is filled 75 with hot water.

The operation is substantially as follows:—The appliance is placed beneath the loaded vehicle and the pawl-and-ratchet device *b*¹—*b*² actuated until the rotation 80 and consequent upward movement of rod *b* bring it into lifting contact with the head-plate *c*¹, the latter being lifted thereby to the extent necessary to raise the vehicle clear of the ground and permit the weighing ac- 85

tion to take place. During this movement, the rods *d* and *d*¹ attached to said plate are carried upward therewith, together with the nuts *d*² and *d*³. The nuts are then turned and lowered upon the rods *d* and *d*¹ 90 until they are caused to bind against the upper face of the cap-plate *e* and are thus locked in place. When this has been done, the pawl-and-ratchet device is actuated in the reverse manner, so as to lower rod *b*, 95

whereupon the weight of the vehicle will be transferred from that rod to the rods *d* and *d*¹, and the cap-plate *e* and springs *e*¹. Thereupon, the said plate *e*¹ is caused to descend, thus moving the rods *f* and *f*¹ in the 100 same direction and rotating the pinions *f*² and the dial hands to indicate the weight. At the completion of the weighing operation, the main or lifting rod *b* is again raised, for the purpose of supporting the head-plate *c* and the load thereon, and of removing the load from the cap-plate and springs. Finally, the nuts *d*² and *d*³ are 105 released from frictional engagement with the cap-plate by being moved upwardly on the 110

rods d and d^1 , thereby allowing the vehicle to return to its original position on the ground.

I claim as my invention:—

- 5 1. In a weighing appliance, the combination, with a load-sustaining plate; of a yieldingly-supported cap-plate associated with the first-named plate; a weight-indicating device operatively connected to the 10 second-named plate; a vertically-movable element arranged beneath said first-named plate, for raising or lowering the same, to transfer the load to said second-named plate; and means for operating said element.
- 15 2. In a weighing appliance, the combination, with a load-sustaining plate, and a support connected thereto; of a weighing gear with which said support is normally loosely engaged; a vertically-movable element arranged beneath said plate, for raising the same; means for operating said element; and means for locking said support to the weighing gear when said plate is raised to transfer the load to said weighing 25 gear.
- 30 3. In a weighing appliance, the combination, with a load-sustaining plate, and a pair of depending rods carried thereby; of a weighing gear with which said rods are normally loosely engaged; a vertically-movable element arranged beneath said plate, for raising the same; means for operating said element; and means for locking said rods to the weighing gear when said plate is raised to transfer the load to said weighing 35 gear.
- 40 4. In a weighing appliance, the combination, with a load-sustaining plate, and a pair of depending rods carried thereby; of a spring-supported cap-plate with which

45 said rods are normally loosely engaged; a weight-indicating device operatively connected to said cap-plate; a vertically-movable element arranged beneath the first-named plate, for raising the same; means for operating said element; and means carried by said rods for locking the cap-plate thereto when said cap-plate is raised, to transfer the load to said cap-plate.

50 5. In a weighing appliance, the combination, with a load-sustaining plate; of a weighing gear associated therewith; a threaded socket member disposed beneath said plate; a vertical rod having its lower end threaded and fitted in said socket, said rod extending toward said plate; and means for rotating said rod, to raise the same and said plate and to transfer the load to said weighing gear.

55 6. In a weighing appliance, the combination, with a load-sustaining plate; and a support connected thereto; of a weighing gear with which said support is normally loosely engaged; a threaded socket member disposed beneath said plate; a vertical rod 60 having its lower end threaded and fitted in said socket, said rod extending toward said plate; means for rotating said rod, to raise the same and said plate; and means for locking said support to the weighing gear when 65 said plate is raised to transfer the load to said weighing gear.

In testimony whereof I have hereunto set my hand in presence of two subscribing witnesses.

CLARENCE SHEPHERD.
